UNITED STATES PATENT OFFICE.

ROBERT JOSEPH FISHER, OF ATHENS, TENNESSEE, ASSIGNOR TO THE
FISHER TYPEWRITER COMPANY, OF TENNESSEE.

TYPE-WRITING MACHINE.

SPECIFICATION forming part of Letters Patent No. 637,749, dated November 21, 1899.

Application filed November 30, 1897. Serial No. 660,272. (No model.)

To all whom it may concern:

Be it known that I, ROBERT JOSEPH FISHER, a citizen of the United States, residing at Athens, in the county of McMinn and State of Tennessee, have invented a new and useful Type-Writing Machine, of which the following is a specification.

My invention relates to type-writing machines of that class designed for bookwork, and consisting, essentially, in an improvement upon the constructions shown and described in Patents Nos. 569,491, 572,535, and 573,868, granted to me October 13, 1896, December 8, 1896, and December 29, 1896, respectively, and Patents Nos. 569,625, 569,626, and 569,627, granted to me on October 20, 1896.

The object of the present invention is to provide an improved ribbon mechanism so constructed as to be automatically withdrawn from a position in the line of vision of the operator after each operation of a printing-key and to be returned to operative position in the path of the type-heads at each operation of a printing-key, whereby the operator has an unobstructed view of the line of writing except during the depression of a printing-key.

A further object of the invention is to provide means for preventing vibration of the type-bar-supporting ring in a direction transverse to the line of writing, and thereby securing an accurate alinement of the impressions made by the printing-type.

Further objects and advantages of this invention will appear in the following description, and the novel features thereof will be particularly pointed out in the appended claims.

In the drawings, Figure 1 is a plan view, partly broken away, of a type-writing machine constructed in accordance with my invention. Fig. 2 is a vertical central section of the same. Fig. 3 is a bottom plan view. Fig. 4 is a detail view in perspective of the ribbon mechanism detached. Fig. 5 is a plan view of the ribbon-spoils and connected parts to show the means for communicating reciprocatory motion to the spoils parallel with the lines of writing. Fig. 6 is a vertical central section of the ribbon mechanism to show the spoils and the means for communicating rotary motion thereto and also to show the connection between the spoils and the carriage.

frame whereby reciprocatory motion is imparted to the spoils in a direction parallel with the lines of writing. Fig. 7 is a detail view in perspective of the rocking trip whereby the ribbon-spool-feeding mechanism is alternately thrown into operative engagement with the spoils for communicating longitudinal feeding movement to the inking-ribbon in opposite directions. Fig. 8 is a detail sectional view of the means for mounting the ribbon-spoils, such section being taken parallel with the axis of the spoils. Fig. 9 is a detail view of one of the ribbon-spool holding or stop pawls detached.

Similar numerals of reference indicate corresponding parts in all the figures of the drawings.

The machine embodying my present invention corresponds in general construction with those shown and described in my former patents above mentioned in that it embodies stationary horizontal parallel tracks 1, arranged transverse to the line of writing and adapted to rest upon the surface of a sheet or page which is to receive the impression of the printing characters, a supporting-frame having front and rear base-bars 2 and 3 and front and rear carriage-guides 4 and 5, said base-bars being provided with alined notches or seats 6, fitted upon the tracks, which carry racks 7 for engagement by the feed-pinion 8 of the line-spacing mechanism, and a carriage 9, having front and rear bearing-rollers 10 and 11, mounted, respectively, upon said carriage-guides for movement parallel with the lines of writing, said carriage supporting a pendent type-bar-supporting ring 12, of crescent shape, upon which are mounted the type-bars 13. Furthermore, the machine embodying the present invention includes, as shown and described in said former patents, a plurality of printing-keys 14, connected by intermediately-pivoted key-levers 15 with draw-rods 16, which are in turn connected with the type-bars and are adapted when the printing-keys are depressed to communicate motion, respectively, to the type-bars to cause their depression to the printing position. The specific construction of the bearing-clips 17 by which the type-bars are mounted upon a type-bar-supporting ring is particularly

shown and described in a copending application, Serial No. 675,729, filed of even date herein, with myself and C. F. Laganke, and forms no part of the invention disclosed herein. The carriage is also provided with a forwardly and rearwardly extending feed-shaft 18, provided at its front and rear ends with pinions 19 and 20, meshing with racks 21 and 22, disposed, respectively, contiguous to the front and rear carriage-guides, any suitable carriage-feeding mechanism being employed in connection with said feed-shaft—such, for instance, as that indicated at 23, and more particularly shown and described in my said former patent, No. 569,825, granted October 20, 1896.

In order to facilitate the adjustment and prompt locking of the line-spacing pinions 8 at the desired interval between the tracks 1, (which obviously are adjustable laterally to 20 suit the width of the surface which is to receive the impression by arranging them in different seats 6 of the base-bars 2 and 3,) I provide the hub of each pinion with a parallel-sided pivotal dog 25, actuated by a spring 25 and normally held thereby in position to engage either of a series of notches 27, formed in said spindle, the pinions being feathered upon the spindle to allow axial adjustment of the former upon the latter, and yet provide for the communication of rotary motion from the latter to the former. The pawls 28 are provided with projecting finger-holds 28, by grasping which the operator is enabled to disengage the pinions to allow axial adjustment thereof to suit the interval between the tracks. The release of the dog causes its immediate engagement with the notch 27 in the plane of which it may be arranged, and hence the prompt locking of each pinion at the desired adjustment. A step-by-step rotary motion may be communicated to the spindle 24 by any suitable line-spacing mechanism, including, for instance, a ratchet-wheel 29 and a pivotal line-spacing lever 30, having a pawl 31 to engage the teeth of said ratchet-wheel.

Mounted upon the hereinbefore-described supporting-frame, preferably by means of terminal brackets 32, is a ribbon-spool spindle 33, which is thus arranged parallel with the lines 50 of writing, and mounted upon this spindle for rotary and axial movement are twin ribbon-spoils 34, upon which are reeled the extremities of the inking-ribbon 35. The spools are preferably mounted upon a sleeve 36, which is fitted to slide upon the spindle 33, the terminal portions of the sleeve being reduced to form journals 37 and the spools being held from displacement, while being free to rotate independently of each other and of the sleeve, 60 by means of removable collars 38, secured to the sleeve by set-screws 39.

As set forth in said copending application, Serial No. 675,729, the type-bar-bearing clips 17, which are arranged in contact with the underside of the type-bar-supporting ring 12, are held in place by a securing-plate 40, which, as shown in Fig. 3, is of sectional construction

and comprises main or terminal members 40^a and an intermediate or short member 40^b, said members being held in place by securing-screws 41. This intermediate securing-plate member 40^b is, however, extended, as shown clearly in said Fig. 3, to form an armed bracket 42, from the extremities of which rise the rear hanger-rods 43, by which the center 75 of the supporting-ring 12 is held in place. The front ends of the supporting-ring are attached to hangers 44. This bracket 42 is also provided with depending stop-pins 45, which extend to a point below the plane of the upper 80 sides of the tracks 1 to limit the movement of the carriage parallel with the lines of writing by contact with the inner surfaces of said tracks, (an equivalent construction being shown and described in my said former patent, No. 569,825.)

The hanger-rods 43, which are of even diameter throughout, serve as supports for the ribbon-spool-operating mechanism, which in the construction illustrated consists of a rock-shaft 46, having arms 47, to the extremities of which are pivoted ribbon-spool-feeding pawls 48 for engagement with the ratchet-teeth of the ribbon-spoils, as clearly illustrated in Figs. 2, 4, and 6. Holding or stop pawls 49 are also preferably used in this connection to prevent backward rotation of the ribbon-spoils during the backward movement of the rock-shaft 46, said holding-pawls being of angular or elbow construction and being loosely mounted upon the rock-shaft, with their extremities held yieldingly by gravity, or any equivalent force, in operative engagement with the teeth of the ribbon-spool ratchets. As it is necessary in order to feed the ribbon 105 longitudinally that one of the spools be allowed to turn in a direction to unreel the ribbon while the other is being fed to reel the ribbon, means must be provided for causing alternate engagement of the ribbon-spool-feeding pawls with their respective ratchets, and hence I employ a rocking trip-lever 50, fulcrumed at an intermediate point and arranged with its arms under the feed and stop pawls for the respective ribbon-spoils. When 115 this trip-lever is tilted to release the feed and stop pawls of one spool, by withdrawing the contiguous arm thereof from contact with said pawls, the other arm is elevated sufficiently to raise the feed and stop pawls of the other ribbon-spool out of engagement whereby the oscillation of the rock-shaft 46 causes the feeding movement of the ribbon in one direction. Obviously the reversal of the trip-lever will change the relative positions of the operating-pawls, whereby the movement of the shaft 46 125 is communicated to the other ribbon-spool to feed the ribbon in the opposite direction. I preferably provide each ribbon-spool with a ratchet on each flange thereof, whereby said 130 spools may be arranged, respectively, at either end of the sleeve 36 or may be reversed in position when the teeth of the ratchets become worn. Any desired tension may be produced

in the ribbon by the adjustment of the collars 38 toward and from the contiguous ribbon-spools. The trip-lever is yieldingly held in either of its adjusted positions by means of a spring 51 engaging a cam-faced projection 52 at the center of the lever, and the lever is preferably provided with terminal finger holds or ears 53 to facilitate the reversal thereof to change the direction of movement of the inking-ribbon.

As above indicated, the ribbon-spool-operating mechanism is carried by the hanger-rods 43, and in order to provide for the attachment of said feeding mechanism with facility to the machine and also to provide any required vertical adjustment thereof with relation to the ribbon-spools I preferably in this connection employ a bracket 54, upon which the rock-shaft 46 and the trip-lever 50 are mounted, said bracket having a horizontal upper arm 55, provided with a pendent rear end 56, upon which the trip-lever is fulcrumed, said horizontal arm serving as a means whereby the spring 52 is attached. The main plate of this bracket 54 is also provided with terminal lateral ears 57, having bearings for the rock-shaft 46, and is secured by means of a screw 58 or its equivalent to a clamp 59^a, having terminal seats for engaging the hanger-rod 43.

It will be seen from the foregoing description that while the machine is of that class wherein the carriage which moves parallel with the lines of writing carries the printing mechanism, consisting of the type bars and keys, the ribbon-spools constituting the inking mechanism are mounted upon the line spacing or supporting frame, which is mounted upon the tracks for movement at right angles to the lines of writing. These ribbon-spools, however, are mounted upon a common spindle and are hence coaxial, and it is necessary from the fact that the intermediate or operative portion of the ribbon does not extend through a distance equal to the lengths of the lines of writing that the spools should be moved coextensively with the carriage during the operation of the machine. To accomplish this movement, I provide the above-mentioned bracket 54 with a feed-arm 59, which projects rearwardly and is provided with a terminal fork 60, fitting in the circumferential groove 61 at the center of the ribbon-spool sleeve between the contiguous sides of the ribbon-spools, all as clearly illustrated in Figs. 5 and 6. Hence with each movement of the carriage during the printing operation the ribbon-spools are simultaneously moved in an axial direction parallel with the path of the carriage without interfering in any way with the rotary movement of the spools under the influence of the feeding mechanism hereinbefore described. This feed-arm 59, which has a bearing upon the sleeve which fits to slide upon the ribbon-spool spindle, has, however, an additional function, residing in the fact that it acts as a brace to prevent rear-

ward vibration of the basket or pendent portion of the carriage, consisting of the type-bar-supporting ring and the type-bars mounted thereon. In other words, the ribbon-spool spindle, which is arranged parallel with the path of the carriage, serves as a guide for the type-bar-supporting ring, and by reason of the interposed feed-arm 59 has a sliding connection therewith by which lost motion in the carriage is eliminated. This bracing or guiding action, however, is assisted by an auxiliary or front guide 62, with which the extremities of the crescent-shaped supporting-ring 60 have a sliding connection, consisting of slides or clips 63, having upwardly-extending blades, which fit in a longitudinal groove 64, formed in the under side of the guide-bar 62. The front and rear guides 62 and 63, with which the type-bar-supporting ring has a sliding connection at its front and rear sides, effectually prevent either linear or torsional vibration of the supporting-ring.

The coaxial arrangement of the ribbon-spools involves a looped arrangement of the intermediate or operative portion of the inking-ribbon, as clearly illustrated in Figs. 3 and 4, the sides of this loop passing, respectively, over and under upper and lower ribbon-guide pins 65 and 66, carried, respectively, by the brackets 54 and 42. In practice these guide-pins are preferably provided with antifriction sleeves or rolls to reduce the frictional contact of the ribbon therewith. After leaving the guide-pin 66 at one side of the bracket 42 the ribbon passes through a plurality of guide-openings in an oscillatory ribbon-guide 67, which is pivotally mounted upon an inward extension or ear 42^a of the securing-plate member 40^b, the hinge connection being indicated in Figs. 2 and 3 at 68. The inner or front end of the oscillatory guide is cut away between forwardly-extending arms 69 to form a space which is spanned parallel with the lines of writing by the central portion of the ribbon, said arm 69 being provided with angle guide slots or loops 70, forming front ribbon-guide openings, while the sides of the looped portion of the ribbon pass through rear guide slots or loops 71. It is also desirable in order to vary the point of contact of the type transversely of the ribbon to employ means for varying said intermediate or central operative portion of the ribbon transversely to the line of writing, and hence the oscillatory ribbon-guide is made of sectional construction, the main section 67^a being pivotally mounted upon the ear 42^a, while the adjustable member 67^b is mounted to slide upon the main member. For this purpose said adjustable member is provided with an ear 72, fitted in a guide 73 on the main member, and is held at the desired adjustment by means of a locking or thumb screw 74.

As above indicated, it is an object of my present invention to provide ribbon-carrying devices of such a construction as to be withdrawn from the line of vision of the operator

after each operation of a printing-key and to retain it out of said line of vision normally or except at such times as the printing mechanism is in operation. A simple means of 5 accomplishing this operation is indicated in the drawings, wherein the rock-shaft 75, from which motion is communicated to the carriage-feeding mechanism, is connected by a push-rod or equivalent connection 76 with the ribbon guide or carrier, said push-rod being provided with a return-spring 77, by which said ribbon guide or carrier is yieldingly held in its inoperative position to maintain the intermediate portion of the ribbon out of the line of vision of the operator. Said push-rod is connected with the rock-shaft 75 by means of a crank-arm 78, and said rock-shaft is actuated by the printing-keys 14 through yoke-levers 79, connected with vertical slides 80, 10 which are in turn connected with crank-arms 81 on the rock-shaft. This rock-shaft is also utilized in the construction illustrated to communicate motion to the ribbon-feeding mechanism, connection being made by means of a 15 crank-arm 82 on the rock-shaft 75, a pull-rod 83, and an arm 84 on the rock-shaft 46. Thus when a printing-key is depressed to operate a type-bar 13 the rock-shaft 75 (which is described in my former patents, above mentioned, as an equalizing-shaft to connect the opposite slides 80) is turned, and thereby actuates the push-rod 76 and lowers the ribbon guide or carrier to bring the intermediate portion of the ribbon into the path of the type-bar which is being actuated, and also actuates the connection 83 to communicate motion to the rock-shaft 46 of the ribbon-feeding mechanism. Inasmuch, however, as the crank-arms 78 and 82 extend in opposite directions 20 it will be seen that while the ribbon guide or carrier is thrown to its operative position during the downward movement of a printing-key said movement of the printing-key turns the rock-shaft 46 of the ribbon-feeding mechanism to draw the feed-paws 48 forward to engage the next tooth of the feeding ribbon-spool. Therefore said ribbon-spool is given a forward step to feed the ribbon when the printing-key is released or during the upward 25 movement thereof after an impression has been made by the type carried by the type-bar.

As a means of arranging the line spacing or supporting frame in such a position as to write upon any desired line of a page or sheet, 30 where such sheet or page is ruled or where it is desired to continue a line already started, I preferably provide the machine with a "line-finder," consisting of a pivotal arm 85, having a head 86, consisting of a straight edge 35 and actuated by a key 87, connected with the arm by a push-rod 88. By depressing this line-finder arm and moving the line spacing or supporting frame in a direction transverse to the lines of writing the head 86 of the arm 40 may be aligned with the desired ruling on a sheet or page without loss of time.

From the above description of the means

for withdrawing the operative portion of the inking-ribbon from the line of vision of the operator it will be seen that the ribbon 70 guide or carrier can be moved to a greater or less extent at each operation of a printing-key to suit said line of vision by varying the length of the crank-arm 78; but as the line of vision is approximately uniform in a given 75 machine I have deemed it unnecessary to provide any means for adjusting the length of said crank-arm. Obviously the minimum movement of the ribbon guide or carrier is desirable in order to accomplish the desired 80 purpose, as by reducing the extent of throw of said guide the resistance offered to the operation of the printing-keys is proportionately diminished. Said resistance, however, is very slight, owing to the fact that the guide or carrier is of light construction and also owing to the fact that it is moved to its operative position during the operation of a printing-key by depression, and hence such operation is assisted by gravity. The guide or carrier is 85 moved upwardly to its inoperative position, and such movement is accomplished without effort upon the part of the operator by the retracting-spring 77.

Various changes in the form, proportion, 90 and the minor details of construction may be resorted to without departing from the spirit or sacrificing any of the advantages of this invention.

Having described my invention, what I claim is—

1. In a type-writing machine, the combination with a carriage mounted for movement parallel with the lines of writing and carrying printing mechanism, of inking mechanism, including ribbon-spools mounted upon a support which is fixed with relation to the carriage and parallel with the lines of writing, and means for imparting axial movement to the spools from the carriage, substantially as 100 specified.

2. In a type-writing machine, the combination with a carriage mounted for movement parallel with the lines of writing and carrying printing mechanism, of inking mechanism, including ribbon-spools, a spool-spindle equal 105 in length to, and parallel with, the path of the carriage and independent thereof, and means for imparting axial movement to the spools, substantially as 110 specified.

3. In a type-writing machine, the combination with a carriage mounted for movement parallel with the lines of writing and carrying printing mechanism, of inking mechanism including ribbon-spools mounted upon a fixed 115 support for axial movement parallel with the lines of writing, and means for imparting axial movement to the spools, substantially as 120 specified.

4. In a type-writing machine, the combination with a carriage mounted for movement parallel with the lines of writing and carrying printing mechanism, of inking mechanism including ribbon-spools mounted upon a com- 130

- mon fixed spindle arranged parallel with the lines of writing, and means for imparting axial movement to the spools, substantially as specified.
5. In a type-writing machine, the combination with a supporting-frame and a carriage mounted upon said frame for movement parallel with the lines of writing and carrying printing mechanism, of inking mechanism including ribbon-spools having a common fixed spindle arranged on the supporting-frame parallel with the lines of writing, and means for imparting axial movement to the spools, substantially as specified. 70
10. 6. In a type-writing machine, the combination with a frame mounted for line-spacing movement, and a carriage mounted for movement parallel with the lines of writing and carrying printing mechanism, of inking mechanism including ribbon-spools mounted upon a fixed spindle on said frame, and means for feeding the spools parallel with the path of the carriage, substantially as specified. 75
15. 7. In a type-writing machine, the combination with a carriage mounted for movement parallel with the lines of writing, and carrying printing mechanism, of inking mechanism, including twin coaxial ribbon-spools, having a common journal-sleeve, a fixed spindle upon which said sleeve is mounted for sliding movement with the carriage parallel with the lines of writing, and means for imparting a step-by-step rotary motion to one of the spools, substantially as specified. 80
20. 8. In a type-writing machine, the combination with a carriage mounted for movement parallel with the lines of writing, and carrying printing mechanism, of inking mechanism including coaxial ribbon-spools, a journal-sleeve upon which said spools are mounted between spaced collars, the collar at one side of each spool being adjustable, a fixed spool-spindle upon which said journal-sleeve is mounted for movement parallel with the lines of writing, and means for communicating motion to the journal-sleeve, substantially as specified. 85
25. 9. In a type-writing machine, the combination with a carriage mounted for movement parallel with the lines of writing, and carrying printing mechanism, of inking mechanism, including ribbon-spools, a spool-spindle arranged parallel with the lines of writing, a journal-sleeve mounted upon said spindle and having reduced terminal portions upon which the spools are revolvably mounted, said sleeve having a fixed central collar, and adjustable terminal collars adapted to bear against the outer surfaces of the spools, means for securing said adjustable collars at the desired adjustment, and means for imparting a sliding motion to the sleeve, substantially as specified. 90
30. 10. In a type-writing machine, the combination with a carriage mounted for movement parallel with the lines of writing and carrying printing mechanism, of inking mechanism including ribbon-spools mounted on a support which is independent of the carriage for movement parallel with the lines of writing, and a feed-arm on the carriage having connection with the spools to impart axial movement thereto, said feed-arm serving also as a brace to prevent rearward vibration of the carriage, substantially as described. 95
35. 11. In combination with the tracks 1, the spindle having notches, the pinions 8 feathered on the spindle, and spring-actuated dogs carried by the pinions to engage the notches, substantially as described. 100
40. 12. In combination with the ribbon-spool spindle, the sleeve shorter than the spindle and fitted to slide thereon, the twin ribbon-spools mounted on the sleeve, to rotate independently of each other and of the sleeve, the removable collars secured to the sleeve and adjustable toward and from the contiguous ribbon-spools to give the desired tension to the ribbon, and means for turning the spools on the sleeve. 105
45. 13. In a type-writing machine, the combination with a carriage mounted for movement parallel with the lines of writing, and carrying printing mechanism, of inking mechanism including coaxial ribbon-spools having a common journal-sleeve mounted for movement parallel with the lines of writing, and a feed-arm on the carriage having an interlocking engagement with said sleeve to impart axial movement to the spools, substantially as specified. 110
50. 14. In a type-writing machine, the combination with a carriage mounted for movement parallel with the lines of writing, and carrying printing mechanism, of inking mechanism including a journal-sleeve mounted upon a spindle for movement parallel with the lines of writing and operatively connected with the carriage, interchangeable ribbon-spools mounted upon said sleeve, and means for imparting rotary motion to either of said spools, substantially as specified. 115
55. 15. In a type-writing machine, the combination with a carriage mounted for movement parallel with the lines of writing, and carrying printing mechanism, of inking mechanism including coaxial ribbon-spools mounted for movement parallel with the lines of writing and to rotate independently of each other and having ratchets, independent feed-pawls and stop-pawls for each spool arranged respectively in operative relation with the ratchets of the ribbon-spools, operating connections between said pawls and the printing mechanism, and trip mechanism for raising the feed and stop pawls of one spool out of engagement, and throwing the feed and stop pawls of the other spool into engagement, for the purpose substantially as specified. 120
60. 16. In a type-writing machine, the combination with a carriage mounted for movement parallel with the lines of writing, and carrying printing mechanism, of inking mechanism, including coaxial ribbon-spools mounted 125

for movement parallel with the lines of writing and having ratchets, feed-pawls arranged respectively in operative relation with the ribbon-spool ratchets, operating connections between said pawls and the printing mechanism, and trip mechanism including a rocking lever having its arms arranged respectively in operative relation with the feed-pawls to remove either of said pawls from operative engagement with its ratchet, and locking devices for the lever, including a cam-faced head and a holding-spring in operative relation with said head, substantially as specified.

17. In a type-writing machine, the combination with a carriage mounted for movement parallel with the lines of writing, and carrying printing mechanism, of inking mechanism including ribbon-spools mounted for axial movement parallel with the lines of writing, an oscillatory ribbon guide or carrier for supporting an intermediate looped portion of a ribbon reeled upon said spools, and having spaced terminal angularly-disposed ribbon-guiding loops, between which an intermediate portion of the ribbon is arranged parallel with the lines of writing, said loops being movable to vary transversely the intermediate portion of the ribbon, a locking device for securing said loops in their adjusted positions, and means for actuating said guide or carrier, substantially as specified.

18. In a type-writing machine, the combination with a carriage mounted for movement parallel with the lines of writing, and carrying printing mechanism, of inking mechanism, including ribbon-spools mounted for axial movement parallel with the lines of writing, and an oscillatory ribbon guide or carrier operatively connected with the printing mechanism and having spaced angularly-disposed ribbon-guiding loops adjustable transversely with relation to the lines of writing, and a locking device for securing said ribbon-guiding loops at the desired adjustment, substantially as specified.

19. In a type-writing machine, the combination with a carriage mounted for movement parallel with the lines of writing, and carrying printing mechanism, of inking mechanism, including ribbon-spools mounted for axial movement parallel with the lines of writing, a hinged ribbon guide or carrier operatively connected with the printing mechanism for oscillatory movement, and having an adjustable section provided with angularly-disposed ribbon-guiding loops and adapted for adjustment transversely to the lines of writing, and means for securing said adjustable member at the desired adjustment, substantially as specified.

20. In a type-writing machine, the combination with a carriage mounted for movement parallel with the lines of writing, and carrying printing mechanism, of inking mechanism, including ribbon-spools mounted for axial movement parallel with the lines of writing, an oscillatory ribbon guide or carrier oper-

atively connected with the printing mechanism and having a main member provided with fixed ribbon-guiding loops, and an adjustable member provided with movable ribbon-guiding loops between which an intermediate portion of an inking-ribbon is held in a position parallel with the lines of writing, and means for locking the adjustable member of the ribbon guide or carrier at the desired adjustment with relation to the fixed guiding-loops, substantially as specified.

21. In a type-writing machine, the combination with a carriage mounted for movement parallel with the lines of writing and having a pendent type-bar-supporting ring, type-bar-bearing clips carried by the supporting-ring, securing-plates spanning the bearing-clips to fasten them to the supporting-ring, one of the securing-plates having an intermediate central section, of inking mechanism, including ribbon-spools, mounted for axial movement parallel with the lines of writing and connected with the carriage for actuation thereby, feed mechanism operatively connected with the printing mechanism for imparting rotary movement to the spools, a bracket carried by said intermediate securing-plate section, hangers depending from the carriage and attached at their lower ends to said bracket for supporting said feed mechanism, a ribbon guide or carrier hingedly mounted upon an extension of said securing-plate section and having ribbon-guiding loops, and connections between said ribbon-guide and the printing mechanism, substantially as specified.

22. In a type-writing machine, the combination with a supporting-frame, a carriage mounted upon said frame for movement parallel with the lines of writing, and printing and inking mechanisms, the former including a pendent type-bar-supporting ring, of a guide-bar attached to the supporting-frame in rear of the type-bar-supporting ring and parallel with the lines of writing, the inking mechanism mounted on the guide-bar, and a sliding connection between said supporting-ring and the guide-bar, substantially as specified.

23. In a type-writing machine, the combination with a supporting-frame, a carriage mounted upon said frame for movement parallel with the lines of writing, and printing and inking mechanisms, the former including a pendent type-bar-supporting ring, of front and rear guide-bars secured to the supporting-frame contiguous to the plane of and respectively in front and in rear of the supporting-ring, and parallel with the lines of writing, the rear guide-bar receiving and supporting the inking mechanism, and sliding connections between said supporting-ring and said front and rear guide-bars to prevent vibration of the supporting-ring transversely to the lines of writing, substantially as specified.

24. In a type-writing machine, the combi-

nation with a supporting-frame, and a carriage mounted upon the supporting-frame for movement parallel with the lines of writing, and carrying printing mechanism including 5 a pendent type-bar-supporting ring, of front and rear guide-bars arranged on the supporting-frame contiguous to the plane of the type-bar-supporting ring, and parallel with the lines of writing, inking mechanism, including 10 ribbon-spools, coaxially mounted for linear movement upon the rear guide-bar, a feed arm supported by the carriage and operatively connected with said ribbon-spools for communicating linear movement thereto, and

for bracing the supporting-ring against rear- 15 ward vibration transverse to the lines of writing, and a sliding connection between the supporting-ring and said front guide-bar for preventing forward vibration of the supporting-ring transverse to the lines of writing, 20 substantially as specified.

In testimony that I claim the foregoing as my own I have hereto affixed my signature in the presence of two witnesses.

ROBERT JOSEPH FISHER.

Witnesses:

JOHN LUTHER EMERSON,

WILLIAM SOLOMON HOGE.
